UNITED STATES PATENT OFFICE.

EMMA WORCESTER DOUGHTY, OF RAMAPO, NEW YORK, ASSIGNOR TO CHENEY BROTHERS, OF SOUTH MANCHESTER, CONNECTICUT, A CORPORATION OF CONNECTICUT.

DESIGN FOR A TEXTILE FABRIC.

40,781.

Specification for Design.

Patented July 19, 1910.

Application filed May 13, 1910. Serial No. 561,267. Term of patent 8½ years.

To all whom it may concern:

Be it known that I, EMMA WORCESTER DOUGHTY, a citizen of the United States, residing at Ramapo, in the county of Rockland and State of New York, have invented a new, original, and ornamental Design for Textile Fabrics, of which the following is a specification, reference being had to the accompanying drawing, forming part thereof.

The drawing illustrates a section or portion of a fabric embodying my new design.

I claim:

The ornamental design for a textile fabric, as shown.

EMMA WORCESTER DOUGHTY.
